UNITED STATES PATENT OFFICE

115,424

DESIGN FOR A TIRE

Bert R. Prall, Winnetka, Ill., assignor to Montgomery Ward & Co., Incorporated, Chicago, Ill., a corporation of Illinois

Application February 9, 1938, Serial No. 74,992

Term of patent 7 years

To all whom it may concern:

Be it known that I, Bert R. Prall, a citizen of the United States, residing at Winnetka, in the county of Cook and State of Illinois, have invented a new, original, and ornamental Design for a Tire, of which the following is a specification, reference being had to the accompanying drawing, forming a part thereof.

In the drawing—

I claim:

The ornamental design for a tire, substantially as shown.

BERT R. PRALL.
